Primary Examiner — Wan Laymon(74) *Attorney, Agent, or Firm* — Fish & Richardson P.C.**CLAIM**

The ornamental design for a controller for an infusion pump, substantially as shown and described.

DESCRIPTION

FIG. 1 is a perspective view of a controller for an infusion pump in accordance with our design.

FIG. 2 is a bottom view of the controller of FIG. 1.

FIG. 3 is a top view of the controller of FIG. 1.

FIG. 4 is a right side view of the controller of FIG. 1.

FIG. 5 is a left side view of the controller of FIG. 1.

FIG. 6 is a front view of the controller of FIG. 1; and,

FIG. 7 is a rear view of the controller of FIG. 1.

The broken lines immediately adjacent the shaded areas represent the bounds of the claimed design while all other broken lines represent environment and are for illustrative purposes only; the broken lines form no part of the claimed design.
